FROST REMOVING TOOL

Roy E. Hammond, Chicago, Ill.

Application July 17, 1947, Serial No. 761,514

1 Claim. (Cl. 219—21)

1

This invention relates to hand tools and more particularly to an electrically heated hand tool for removing frost and the like from cold surfaces such as the cooling surfaces and coils of refrigerators and frozen food cabinets.

An important object of my invention is to provide a simple and inexpensive hand tool by means of which accumulations of frost and ice may be quickly and effectively removed from sub-freezing surfaces with a minimum of physical effort.

Another object of my invention is to provide a tool of this character by which said frost and ice may be removed from such surfaces while the latter remain at sub-freezing temperatures.

Still another object of my invention is to provide a heated hand tool by means of which frost and ice may be removed from surfaces within a refrigerated space without materially increasing the temperature in said space.

A further object of my invention is to provide a tool of these characteristics shaped to prevent an accumulation of frost or ice thereon while the same is being operated to remove said frost or ice from a refrigerated surface.

Other objects and advantages of the invention will be apparent from the following description of a preferred embodiment thereof, taken in connection with the accompanying drawing, in which:

Fig. 1 is a top plan view of a hand tool incorporating my invention; and

Fig. 2 is a sectional view thereof taken substantially on the line 2—2 in Fig. 1.

As thus illustrated the tool has a metallic tubular arm 11 upon one end of which is mounted a hollow handle 12 of wood or other insulatory material shaped to be comfortably held in the hand. A ring 13 may be fitted over one end of the handle in a well known manner for purposes of reinforcement. A passage 14 is drilled or otherwise formed in the other end of the handle, and within the passage and protruding therefrom is a coiled spring protective member 15 of a suitable commercial type through which extends a double strand electric cord shown generally at 16. An ordinary male plug 17 is attached to the external end of the electric cord and the exposed portion of said cord may be provided with a heavy protective covering 18.

From the inner end of the protective member 15 the cord extends through a hollow 19 in the handle and thence through the interior of the arm 11 to a head, shown generally at 21, within which said cord is electrically connected to an electric heating element indicated by the numeral

2

20. Said head may be of multiple or single piece construction having disposed on the forward portion thereof a straight parting edge 22 which extends laterally across the entire width of said head. The parting edge is constructed of a metal which has a very high coefficient of thermal conductivity. Copper or aluminum are suitable for this purpose inasmuch as they are inexpensive and have coefficients of thermal conductivity much higher in value than those of any of the other common metals. Copper, for example, has a coefficient of thermal conductivity in excess of the value of 200 and aluminum has a similar coefficient greater than 100, the value of said coefficient varying slightly with changes of temperature as is well known to those acquainted with the art. I prefer to use a single-piece head formed of cast aluminum or copper having the tapered parting edge 22 formed thereon as an integral part of the head.

A socket shown generally at 23 may be provided on the upper portion of the head to enclose a space 24 for receiving an end of the arm 11. The arm may be secured to the head by means of screws 25 and 26 which penetrate walls 27 of the socket and are threaded into the arm. The bottom surface of said head is flat as at 28 and the upper contours of the head are rounded to prevent an accumulation of ice and frost thereon when said frost or ice is removed from a cold surface by the tool in a manner hereinafter described.

The heating element 20 is arranged within the head along substantially the entire length of the parting edge and as close to the latter as practical. Said heating element may be of any suitable commercial construction and, for the sake of economy and simplicity of construction, may be cast within the head as an integral part thereof. A heating element suitable for this type construction may comprise the usual loop of electrical resistance wire 29 enclosed within a tubular insulatory covering 30 composed of a magnesium oxide compound well known to the art. The wire itself may be of chrome-nickel steel or other material having high heat resistant properties, and heat resistant porcelain beads 31 may be provided as insulation for the wires of the electric cord adjacent the point at which the latter is attached to the heating element.

With the plug 17 connected to a source of electric current (not shown) the parting edge 22 may be pressed, with a natural and easy scraping motion, against formations of ice or frost adjacent a surface from which said frost or ice is to be

cleaned. Because the heating element is in intimate association with the parting edge and the metal forming the edge has a high coefficient of thermal conductivity, a minimum of thermal resistance will exist between the heating element and the line at which the parting edge engages the frost or ice. Heat will thus be conducted through said edge to the frost or ice at a maximum rate to melt the same along a thin line and cause the latter to separate from the surface. Because the rate at which heat will be conducted to said frost or ice is great, the temperature of the parting edge need not be high.

It will readily be understood that substantially all of the heat generated by the heating element will be dissipated in the melting of the frost and ice along the line of separation and that a minimum of said heat will be conducted to the surfaces being cleaned or radiated into the refrigerated space about the surfaces. Cold cooling surfaces within refrigerators and the like may thus be cleared of frost and ice with my tool while the temperatures of said surfaces and that of the refrigerated space surrounding them remain substantially unchanged.

The foregoing detailed description has been given for clearness of understanding only and no unnecessary limitation should be understood therefrom, but the appending claim should be construed as broadly as permissible in view of the prior art.

I claim:

A tool for removing frost from a surface com-

prising: a handle; a head on said handle, said head having a flat bottom surface and rounded upper surfaces; a parting edge on said head for separating said frost from said surface; and a source of heat in intimate association with said edge for heating the latter, said edge and head being integral and being constructed of material having a coefficient of thermal conductivity of a value greater than one hundred and said source of heat being disposed within said material and parallel to said edges, said head being elongated transversely of the handle and said source of heat comprising an electrical heating element positioned in the lower front part of said head, whereby to concentrate the heat in said parting edge, and extend substantially the full length of the latter.

ROY E. HAMMOND.
